STEAM OR HOT WATER BOILER

John W. Lockett, Oswego, N. Y., assignor to Fitz-gibbons Boiler Company, Inc., New York, N. Y., a corporation of New York

Application December 21, 1933, Serial No. 703,356

11 Claims. (Cl. 122—32)

The present invention relates to boilers and has for an object to make improved provision for heating water for a separate supply as, for example, for household uses.

5 The invention aims to provide an arrangement whereby an auxiliary water supply unit mounted in the boiler below the water line is surrounded by the hottest water in the boiler and further to provide means for automatically increasing the 10 fire if and when a considerable amount of cold water is drawn through the heating unit. To this end the invention provides means whereby the current of water induced in the boiler by the heating of the boiler water flows from 15 a region of maximum heating directly to and about the auxiliary water heating unit and further provides a thermostat connected for automatically increasing the fire when the boiler water about the water heater is cooled below a predetermined temperature by cold water flowing 20 through the water heater.

In order that the thermostat may respond promptly to changes in the temperature at the heating unit, it is arranged to be acted upon by 25 a current of water flowing past the water heater unit.

The invention has been developed more particularly in connection with the construction of a boiler designed more particularly for the use 30 of an oil burner and for convenience of disclosure such an embodiment of the invention will be more particularly described. It will be understood, however, that the particular description is illustrative merely and is not intended as defining the limits of the invention.

35 The nature and objects of the invention will be better understood from the following description of the selected embodiment for the purposes of which description reference should be had to the accompanying drawings forming a part hereof and in which—

Figure 1 is a vertical sectional view taken longitudinally through a fire tube boiler embodying the invention.

40 Fig. 2 is a sectional plan view showing the position of the heating unit in the boiler, taken on the line 2—2 of Fig. 1.

Fig. 3 is a detail view of an instantaneous water heating unit.

45 Fig. 4 is a sectional view taken on the line 4—4 of Fig. 3.

Fig. 5 is a sectional view taken on the line 5—5 of Fig. 3.

50 Fig. 6 is a sectional view through the thermos stat chamber taken on the line 6—6 of Fig. 2,

Fig. 7 is a sectional view taken on the line 7—7 of Fig. 6.

Fig. 8 is a detail view of a tank heater unit, Fig. 9 is a sectional view taken on the line 5

9—9 of Fig. 8. In the embodiment shown for the purposes of illustration, the boiler having a combustion chamber 5 with an oil burner 6, a water chamber 7 and fire tubes 8 is equipped with a water heating unit 10 which may be either an instantaneous heating unit as shown in detail in Figs. 3 and 4 or a tank heating unit as shown in Figs. 8 and 9 connected to a water supply tank to maintain hot water therein. At the front of the boiler a steel or iron box opening 11 is welded 10 securely or otherwise fitted to the boiler shell and provides an opening into the boiler to receive the water heating unit 10 and a flange 12 to which the heating unit is secured. At the rear of the boiler a bracket 13 supports the rear 20 end of the heating unit.

The instantaneous heating unit is shown as consisting of a number of parallel tubes 14 arranged in two planes and preferably so connected that the water flows through all of the tubes in 25 series. All of the tubes are connected to the single header at the front of the furnace but at the opposite ends they are connected separately in pairs to permit differential expansion. The header of the water heater has a flange 15 which 30 fits against and is readily bolted to the flange 12 of the member 11. The inlet and outlet 16 and 17 may be turned to the right or left depending upon whether the water supply is more convenient to the one side or the other of the 35 boiler.

The tank heating unit is constructed to be secured alternatively into the same position as the instantaneous heater unit. As shown in Figs. 8 and 9, it is in general similar to the instantaneous 40 unit and comprises a header 19 and tubes 20 but several tubes are connected in parallel as indicated in Fig. 9. The flange 21 of the header is similar to the flange 15 and has similar bolt holes.

45 The heating unit of either type is positioned preferably horizontally above the crown sheet 22 but below the water line. Deflector plates 23 and 24 are positioned in the boiler and extend toward the heating unit in a position to cause 50 the current of water induced by the heat transmitted from the combustion chamber at the sides and along the crown sheet to the adjacent boiler water to be directed against the tubes of the water heater. Obviously when the combus- 55

tion chamber is hot a substantial current of water will be induced up the sides of the combustion chamber inwardly between the crown sheet and the deflector plates and up past the 5 heater tubes. In the arrangement shown the section of the water chamber above the crown sheet is cylindrical and the deflector plates extend generally parallel to the crown sheet and fit closely against the boiler shell to which they 10 are spot welded but this arrangement can be varied as may be desired provided a current of the freshly heated water is directed to the heating unit.

It is a feature of the invention that a thermostat 15 is so arranged within the boiler that if the water about the heating unit becomes chilled by a considerable flow of cold water through the heating unit the thermostat will cause the fire to be increased. As shown a thermostat 25 20 within the boiler is arranged to be acted upon by a current of water flowing from around the tubes of the heating unit to and around said thermostat. The thermostat may be positioned in a chamber into which a current of the boiler water 25 25 from around the tubes is caused to flow. Such a chamber is formed in the boiler shown by providing an auxiliary trough-shaped deflector member 26 beneath one of the substantially horizontal main deflector plates 23, 24. The edges 30 of the trough are spaced about half an inch from the plate to form slots 27, 28, lugs 29, 30 being provided at the inner end to bear against, and provide a point of attachment to, the plate 24. Obviously this arrangement may be varied.

It has been found in practice that a satisfactory flow of the boiler water from about the heater unit into the thermostat chamber is induced in an arrangement such as shown in the drawings and above described. Probably the flow 40 of the heat induced current of water against the trough-shaped deflector creates a slight suction at the slots 27, 28. Probably also the current inwardly between the crown sheet and the deflector plate 23 on the opposite side assists in causing a flow into the thermostat 45 chamber since at this particular point this flow is not opposed by the flow of water from between the crown sheet and the deflector plate 23 on the opposite side assists in causing a flow into the thermostat 50 chamber since at this particular point this flow is not opposed by the flow of water from between the crown sheet and the plate 24. Probably also the cold water about the heater tubes when water is drawn in substantial quantity tends to 55 flow down onto and along the trough into the thermostat chamber. An operative connection between the thermostat and the oil burner control, whether a valve, electric motor or other responsive device is provided whereby upon cooling 60 of the thermostat by a flow of cold water from about the water heating unit the oil burner control will be correspondingly actuated and when the thermostat is again heated above the critical point the control will be released to permit shutting off of the burner if the control is not at that time held in actuated position under control of another thermostat or by other means.

Ordinarily it will not be necessary to provide a second thermostat within the boiler whether 70 above or below the water line to insure the maintenance of a predetermined temperature at another part of the boiler although obviously certain advantages for special installations might be gained thereby.

The capacity of the boiler as such and of the

water heating unit may be so related that the full capacity is required by the water heater when a considerable amount of water is being drawn. In practice this will not be objectionable for in installations of the type for which such 5 boilers and heating units are designed there will be relatively little occasion for continuously drawing water for long periods, furthermore there is the advantage that the drawing of water will not cause an undesired making of steam with 10 resultant delivery of undesired heat.

A small opening 30' may be provided at the outer edge of each of the deflector plates 23, 24 against the boiler shell to prevent pocketing of water above the plates when draining the boiler 15 or pocketing of steam beneath the plates in use and a similar opening 31 may be provided in the trough 26. Possibly the opening 31 plays a part in the circulation of water through the trough 26.

It is to be noted that in operation due to the fact that the thermostat is not too close to the water heating unit the drawing of a small amount of water through the heating unit will not cause the oil burner to be actuated. The moderate 25 time lag between the drawing of water and actuation of the thermostat is obviously of substantial advantage for this reason but the lag is not sufficient to provide unsatisfactory operation when a considerable quantity of water is drawn. 30

The boiler shown may be used with entire satisfaction and economically for maintaining a supply of hot water for household purposes even in summer when no heat is desired in the house.

I claim:

1. A boiler having a combustion chamber and a water chamber thereabove with a horizontal crown sheet between said chambers, a water heating unit having water tubes extending horizontally above said crown sheet, and deflector plates 40 extending generally parallel to said crown sheet toward said water tubes to direct a current of water heated by the crown sheet to the space around said water tubes.

2. In a boiler the combination with a water 45 heating unit projecting into the boiler below the water line of a thermostat also projecting into the boiler below the water line and means for directing a flow of water from around the water heating unit to the thermostat whereby the thermostat is responsive to changes in the water immediately around the water heating unit.

3. A boiler having a combustion chamber and a water chamber with a crown sheet therebetween, a water heating unit having tubes extending parallel to said crown sheet and a deflector plate arranged to guide a current of water along said crown sheet to said water heating tubes, a thermostat and means for directing a flow of water 60 from around the water heating tubes to the thermostat.

4. A boiler having a combustion chamber and a water chamber thereabove with a horizontal crown sheet between said chambers, a water heating unit having water tubes extending horizontally above said crown sheet, deflector plates extending generally parallel to said crown sheet toward said water tubes to direct a current of water heated by the crown sheet to the space around 70 said water tubes, a thermostat and means for directing a current of water from the space around the water tubes to the space around the thermostat.

5. A boiler having a combustion chamber and 75

5 a water chamber surrounding the combustion chamber at the top and sides thereof, a water heating unit having a series of tubes extending above said combustion chamber within the water chamber, means for directing a current of water from adjacent the walls between the combustion chamber and water chamber into contact with the water heating tubes, a thermostat and means for directing a current of water from around the 10 water heating tubes into contact with the thermostat.

6. A boiler having a combustion chamber and a water chamber surrounding the combustion chamber at the top and sides thereof, a water heating unit having a series of tubes extending above said combustion chamber within the water chamber, deflector plates arranged to form a thermostat chamber and means for directing a flow of water from contact with the water tubes 15 to said thermostat chamber and a thermostat in said thermostat chamber.

7. In a boiler the combination with a water heating unit projecting into the boiler below the water line, of a main deflector plate arranged to direct a current of hot water against the water heating unit, and a trough-shaped auxiliary deflector member positioned beneath and adjacent the main deflector plate to provide thereagainst a thermostat receiving chamber extending toward the water heating unit, the edges of the deflector member being spaced slightly from the main deflector plate.

8. A boiler having a combustion chamber and a water chamber with a crown sheet therebetween, a tubular water heater extending horizontally and centrally above the crown sheet, a pair of deflector plates extending from the sides

of the boiler toward the heater unit and generally parallel to the crown sheet to guide a current of water toward the heater unit, and an auxiliary deflector member extending beneath one deflector plate and toward the heating unit to provide a thermostat chamber between said auxiliary deflector member and the deflector plate, the edge of said auxiliary deflector member being spaced slightly from the main deflector plate. 5

9. A boiler having a crown sheet, a heating unit 10 removably mounted in the boiler above and substantially parallel to the crown sheet, and a deflector plate extending generally horizontally above the crown sheet arranged to direct a current of hot water against the heating unit, the 15 boiler being formed with a flanged opening to receive the heating unit and the heating unit having a header formed with a flange fitting the flange of the boiler opening, substantially as described. 20

10. In a boiler having a combustion chamber and a water chamber the combination with a water heating unit extending horizontally into the water chamber below the water line of a deflector plate extending in a generally horizontal 25 direction arranged to deflect a rising current of water against the water heating unit.

11. A boiler having a combustion chamber and a water chamber thereabove with a horizontal crown sheet between said chambers, a water heating unit having water tubes extending horizontally above said crown sheet, and a generally horizontal deflector plate extending across a major portion of the boiler arranged to direct a current of hot water against the water heating 30 unit. 35
